United States Patent Office

Des. 184,287
Patented Jan. 20, 1959

184,287

PHOTOGRAPHIC COPYING APPARATUS OR SIMILAR ARTICLE

Courtney A. Leubner, Milwaukee, Wis., and Karl M. Maiershofer, Norridge, Ill., assignors to Polaroid Corporation, Cambridge, Mass., a corporation of Delaware

Application January 27, 1958, Serial No. 49,417

Term of patent 14 years

(Cl. D61—1)

F I G. 2

FIG. 3

Figure 1 is a front perspective view of a photographic copying apparatus or similar article showing our new design;

Figure 2 is a rear perspective view thereof; and

Figure 3 is a front perspective view of the apparatus in operative position.

The essential features of our design reside in the parts shown in full lines, certain other features being shown in dotted lines for convenience of illustration.

We claim:

The ornamental design for a photographic copying apparatus or similar article, substantially as shown and described.
